UNITED STATES PATENT OFFICE.

HYLTON A. BRISCO AND CHARLES J. ERICKSON, OF SAN FRANCISCO, CALIFORNIA.

DEEP-WELL PUMP.

No. 872,326.

Specification of Letters Patent.

Patented Dec. 3, 1907.

Application filed December 28, 1906. Serial No. 349,813.

To all whom it may concern:

Be it known that we, H. A. BRISCO and C. J. ERICKSON, citizens of the United States, residing at San Francisco, in the county of San Francisco and State of California, have invented new and useful Improvements in Deep-Well Pumps, of which the following is a specification.

This invention relates to a deep well pump, the object of the invention being to provide a double acting pump of such construction that the greatest quantity of water or other liquid will be elevated at each complete stroke of the pump.

[15] An important feature of this invention is that in connection therewith only a single plunger rod is used while heretofore for double acting pumps two such plunger rods have been ordinarily used. This improvement [20] simplifies the construction and reduces the expense of manufacturing and installing the pump.

A further important improvement is that the cylinder used for the pump is so constructed as to permit of the greatest possible diameter of cylinder being introduced into a well of given size; moreover the construction of the cylinder is simple and cheap.

{ 30} A further important feature is that with this construction there is no space for water to remain motionless or any sand or other solid material to accumulate.

A further object of the invention is to provide a pump, the whole of the working parts [35] of which can be withdrawn from the well by drawing up the plunger rod.

In the accompanying drawing, Figure 1 is a vertical section of the pump; Figs. 2, 3, 4, and 5 are horizontal sections of Fig. 1 on the [40] line 2—2, 3—3, 4—4, and 5—5 respectively, the last named figure showing half of the cylinder.

Referring to the drawing, 1 represents the discharging pipe, the lower end of which is [45] screwed into a casting 2 forming the upper head of the outer cylinder 3, which is screwed at the top upon the outside of said head, and in like manner the lower end of the cylinder is screwed on the outside of the lower head 4 thereof.

5 indicates a cage which rests with a taper fit within the upper head 2. Upon a valve seat at the upper end of said cage rests an an-

nular rubber valve 6 depressed by a spiral spring 7, which is supported by a flanged ring 8 secured to the upper edge of said cage. In the lower end of the valve cage 6 is screwed a spider 9, forming a second valve seat, upon which rests a rubber valve 10, which surrounds a sleeve 11 extending upwards from the hub of the spider, and carrying a stuffing box 12 for the plunger rod 13, the valve 10 rising and falling round said sleeve and being depressed by a coiled spring 14, supported by said stuffing box 12. To the lower end of said plunger rod 13 is screwed a plunger 16, a nut 17 being screwed upon the extreme end of the rod, said plunger having passages 18 closed by an annular rubber valve 19, depressed by a coiled spring 20 supported by a 70 collar 21 on the rod 13. Said plunger reciprocates within the inner cylinder 22, which is supported by being screwed at its upper end to the lower end of the cage 5. Said inner cylinder 22 extends downwards and terminates at a suitable distance above the upper end of the lower head or casting 4, to permit of the water freely passing therebetween. The annular space 23 between said inner and outer cylinders forms the upward force conduit up which the water is forced on the down stroke of the piston. Said water thus forced upwards in this annular space passes through openings 24 formed in the upper head, with which openings register ports 25 formed in 80 the cage 5. It is these ports 25 that are closed by the valve 6.

Within the lower end of the plunger 16 is secured a suction tube 29, which moves within a tubular guide 30 provided with a stuffing box 31, said guide forming the central part of a spider 32, seated within the lower head 4. Screwed upon the lower portion of said spider is an induction pipe 33. Closing the passages 34 through the spider is a rubber valve 35 depressed by a coiled spring 36 supported by the lower edge of the stuffing box 31. Upon the lower end of the suction tube is secured an annular shoe 37.

It will be seen that by drawing up the 100 plunger rod, the whole of the working parts can be drawn out of the well casing. In such cases, first, the plunger which is attached to the plunger rod reaches the lower edge of the cage 6, so that said cage also ascends with the plunger rod. Therefore also

the inner cylinder 22 also ascends. The suction tube 29, being secured to the plunger, also ascends, and the shoe 37 reaching the lower edge of the spider 31 carries with it the spider, and the induction tube 33 secured thereto. This enables all the working parts to be withdrawn from the cylinder for repairs or other purposes.

The operation of the apparatus is as follows:—When the plunger descends, it forces the water down through the space below the edge of the inner cylinder and then up in the annular space 23 between the inner and outer cylinders and through the ports 25 into the discharge pipe, raising the valve 6, the valve 10 being at that time closed. Also upon said downward movement of the plunger, water is drawn into the interior of the cylinder 22 between the valves 19 and 10, the valve 19 being then opened. Upon the upward movement of the plunger, said valve 19 is immediately closed and water is forced out from said interior of the cylinder 22 up past the valve 10 into the discharge pipe and at the same time a suction is created in the annular chamber 23 between the inner and outer cylinders on account of the upper valve 6 being closed, thus causing the lowest valve 35 to rise against its spring and admitting water to said annular chamber. Then upon the return movement of the piston the operation is repeated.

We claim:—

1. In a deep well pump, the combination of inner and outer cylinders, spaced from each other to form an annular uplift space, the bottom of the inner cylinder being spaced from the outer cylinder to permit the water to pass around said bottom into said annular space, a hollow plunger sliding in the inner cylinder and carrying in its lower end a suction tube, a valve closing the upper end of said plunger, a second valve spaced above the first valve, a guideway for said suction tube having a port, a valve closing said port, a guideway for the plunger rod having a port leading from the annular space between the cylinders, a valve closing said latter port, said guideway having an upward extension with an inwardly extending flange, and a coiled spring abutting against said flange and depressing the valve, substantially as described.

2. In a deep well pump, the combination of outer and inner cylinders, a port leading upwards from the annular space between the outer and inner cylinders, a valve seated on said port to close the same, a hollow plunger reciprocating in the inner cylinder, said plunger carrying a suction tube and having at the top a port, a valve seated on said port to close the same, the bottom of the inner cylinder being spaced from the outer cylinder to form a passageway for the water to pass into

the annular space between the two cylinders, 65 a guideway for the suction tube carried by the plunger, said guideway having a port, a valve closing said port, a guideway for the plunger rod above the plunger, said guideway having a port and a valve seated on and closing said port, substantially as described.

3. In a deep well pump, the combination, with an outer casing, of an inner casing, a plunger reciprocating therein, a suction tube carried thereby, said inner casing plunger 75 and suction tube dividing the interior of the outer casing into two chambers, a valve for each chamber arranged to open automatically by the pressure of the liquid upon the downward movement of the plunger to permit liquid to pass upwards in said chamber and to close automatically upon the return movement of the plunger, and a valve for each chamber, arranged to open automatically by the pressure of the liquid upon the 80 upward movement of the plunger to permit the liquid to pass to one chamber, and to force it from the other, said valve being arranged to close automatically upon the return movement of the plunger, substantially 90 as described.

4. In a deep well pump, the combination, with an outer casing, of an inner casing, a plunger reciprocating therein, a suction tube carried thereby, said inner casing plunger 95 and suction tube dividing the interior of the outer casing into two chambers, a valve for each chamber arranged to open automatically by the pressure of the liquid upon the downward movement of the plunger to permit liquid to pass upwards in said chamber and to close automatically upon the return movement of the plunger, and a valve for each chamber, arranged to open automatically by the pressure of the liquid upon the 100 upward movement of the plunger to permit the liquid to pass to one chamber, and to force it from the other, said valve being arranged to close automatically upon the return movement of the plunger, substantially 105 as described.

5. In a deep well pump, the combination, 115 with an outer casing, of an inner casing, dividing the interior of the outer casing into two chambers, an apertured plunger reciprocating within the inner casing, said aperture leading to the interior of said inner casing, a 120 valve seat permitting the passage of liquid from the annular space between the inner and outer casings, a valve closing the aperture in the plunger and a valve closing the 125 valve seat, both adapted to be opened when the plunger descends, valve seats through which the water passes from the interior of the inner casing and to said annular chamber,

and valves on said valve seats adapted to be opened automatically by the pressure of the water upon the upward movement of the plunger, and means carried by the plunger for raising with the plunger rod all of the said valves and the valve seats therefor, and the suction tube and inner casing, substantially as described.

In testimony whereof we have hereunto set our hands in the presence of two subscribing witnesses.
